SINKER OPERATING MEANS FOR KNITTING MACHINES

Edward Peloquin, Elizabeth City, N. C., assignor to Scott & Williams, Incorporated, New York, N. Y., a corporation of Massachusetts

Application April 25, 1938, Serial No. 204,166

10 Claims. (Cl. 66—49)

This invention relates to machines for knitting hosiery having reinforced portions, as at a high splice and the sole, and more particularly to means for operating sinkers in such machines and it is an object of this invention to provide a sinker operating means arranged to so operate the sinkers in relation to the needles taking the reinforcing yarn in the knitting of a course that the sinker wales are lengthened at such needles so as to render the knitting of the main and reinforcing yarns easier and without danger of cutting or breaking the yarns. It is a further object of this invention to provide a sinker operating means which operates the sinkers as described irrespective of changes in the number of needles taking the reinforcing yarn in a course and which does not operate the sinkers adjacent the needles not taking the reinforcing yarn.

In the drawings:

20 Fig. 1 is a partial view in elevation of a Scott and Williams machine for knitting hosiery having a tapered high splice and a reinforced sole and which is equipped with sinker operating means in accordance with this invention;

25 Fig. 2 is a partial top plan view of the structure shown in Fig. 1, some parts being broken away to show other parts more clearly.

Fig. 3 is a fragmentary view in elevation showing part of the mechanism for operating the finger for the reinforcing yarn and the sinkers during each revolution of the needle cylinder in the knitting of a high splice and a reinforced sole;

30 Fig. 4 is a fragmentary view in elevation showing part of the means for adjusting the operation of the yarn finger and sinker operating means for different lengths of reinforcing;

35 Fig. 5 is a fragmentary view in elevation showing part of the operating means for the yarn finger for the reinforcing yarn and the ratchet wheel of Fig. 4; and

40 Fig. 6 is a partial vertical sectional view of the sinker ring and needle cylinder.

In the drawings the invention is shown in connection with a Scott and Williams circular knitting machine, only such parts of the machine being shown as are necessary to illustrate the invention. As shown, a bedplate B mounted on a frame A supports a needle cylinder 260 having needles N and operated by gearing, not shown, from the main drive shaft 20 which rotates synchronously with the needle cylinder. A dial D, driven in the usual manner from the main drive shaft by a suitable driving means, not shown, is also provided. Yarn fingers F¹, F², etc., are pivotally supported on a pin 21 mounted in the

standards 550^a projecting from the latch guard ring 550. Push rods 460 operated by cams on the main pattern drum 120 control operations of the yarn fingers F¹, F², etc., to present and withdraw the yarns from the needles.

In the arrangement shown the yarn finger F² supplies the main or body yarn to the needles and its push rod 460 is operated by the usual cams on the main pattern drum 120. The yarn finger F¹ feeds the reinforcing yarn for the high splice and double sole to the needles and as this yarn is fed for only a portion of each revolution in which it is introduced to the needles means are provided for operating its push rod 460 during each of a plurality of revolutions of the needle cylinder. The push rod 460 for the yarn finger F¹ is provided with a projecting lug 460^a adjacent its lower end and positioned to be engaged by one end of a lever 26 pivotally mounted on a bracket 27 supported from the machine frame A. The other end of the lever 26 is positioned to be engaged by an end of a lever 28 pivotally mounted on a pin 29 fixed in a movable supporting rod 30. The other end portion of the lever 28 is recessed, as at 28^a, a short distance inwardly from the end of the lever to receive a cam 32 mounted on a lever 34 and has a projecting cam engaging portion 28^b positioned to be engaged by the cam 32. The lever 34 is pivotally mounted on a pin 36 fixed in the frame A and at its outer end carries a roller 34^a which is held by a spring 38 in engagement with a cam 40 fixed on the main drive shaft 20.

The rod 30 has one end pivotally connected to an end of a link or support 42 which is pivotally mounted at its other end on the pin 36. Adjacent its other end the rod 30 is slotted, as at 30^a, to receive a supporting pin 44 which is mounted in a bracket carried by the frame A and at its end the rod 30 has, adjustably mounted therein, a pin 30^b which engages a cam 46. The cam 46 and a ratchet wheel 48 to which it is fixed are rotatably mounted on the pin 44 and are operated by a pawl 50 which is connected to the lever 34 to be operated thereby and is held in contact with the ratchet wheel 48 by a spring 52. A spring pawl or 45 detent 54 mounted on an arm 55 fixed on the pin 44 and engaging the ratchet wheel 48 prevents reverse rotation of the ratchet wheel 48 and cam 46.

The cam 40 being fixed on the main drive shaft 50 rotates in synchronism with the needle cylinder 260 and operates the lever 34 once for each revolution of the needle cylinder, causing the pawl 50 to be operated to advance the ratchet wheel 48 and cam 46 step by step with each revolution.

lution of the needle cylinder. Operation of the lever 34 also shifts the cam 32 with respect to the lever 28 causing the cam 32 to oscillate between a position under the cam engaging portion 28^b and a position in the recess 28^a. This movement of the cam 32 rocks the lever 28, causing the lever 28 to rock the lever 26 and lower and raise the push rod 460 and the yarn finger F¹ which feeds the reinforcing yarn to the needles. A complete operation takes place once for each revolution of the cam 40 causing the yarn finger F¹ to be operated to feed the reinforcing yarn to the needles for a portion of each revolution of the needle cylinder during which the operation takes place. The lever 28, however, is mounted on the rod 30 which carries the pin 30^b in engagement with the cam 46 so as the ratchet wheel 48 and cam 46 are rotated the rod 30 is shifted carrying with it the lever 28 so that the position of the cam engaging portion 28^b of the lever 28 is shifted with respect to the cam 32 and the period during which the cam 32 travels in the recess 28^a of the lever 28 and the reinforcing yarn is supplied in a revolution of the needle cylinder is changed.

As it is not desired to operate the ratchet wheel 48 and cam 46 during the knitting of the stocking leg, heel, toe and reinforced portions of uniform width the ratchet wheel 48 is provided with cam surfaces 48^a, 48^b and 48^c, so positioned as to be engaged by the pawl 50 at such times as the ratchet wheel 48 and cam 46 are not to be operated. To shift the cam surface past the pawl 50 so as to permit the pawl 50 to operate the ratchet wheel 48 and cam 46 there is provided a gear wheel 56 operated by a gear train 58 from the main pattern drum 120 and having a pin 59 which engages an abutment 60 fixed on the ratchet wheel 48. The gear train 58 is such that the gear wheel 56 makes a complete revolution for each revolution of the main pattern drum 120. There is also provided a pin 62 on the ratchet wheel 48 positioned to be engaged by a dog or pawl 64 pivotally mounted on a lever 66 and held in position to engage the pin 62 by a spring 68. The lever 66 is pivotally supported on the frame A in position to be engaged by a cam (not shown) on the main pattern drum 120 and operated to rotate the ratchet wheel 48 by the engagement of the dog 64 and pin 62 and shift a cam surface past the pawl 50.

With a reinforcing yarn being presented to the needles for a portion of each revolution of the needle cylinder there will be difficulty in knitting both the body and reinforcing yarns if, when both yarns are being knit, the stitch is kept of a length suitable for knitting the body yarn alone. If the stitch is kept of a length suitable for the knitting of both yarns, the unenforced portions of the courses will be too loose. There is provided, therefore, a means for lengthening the stitch length at the needles taking the reinforcing yarn while the stitch is kept at the usual length at the needles knitting only the body yarn. The means for lengthening the stitch during the knitting of the reinforcing yarn comprises means for forcing inwardly, to a greater extent, the sinkers s which hold the loops at opposite sides of the needles taking the reinforcing yarn. The sinkers s are mounted in the sinker ring 295 and are normally moved inwardly by a fixed cam 307 in the sinker cam cap 300 sufficiently to provide for loops of the desired length for the knitting of the body yarn alone. To move the sinkers in further during the knitting of the reinforcing yarn in order that they may lengthen the loops

drawn, there is provided a cam 306 which is pivotally mounted on the cam ring 300 and projects through a slot formed in the cam 307 so as to engage the butts of the sinkers and force the sinkers inwardly. A pin 306^a projecting from the cam 306 limits the movement of the cam 306 in a direction to force the sinkers inwardly. To operate the cam 306, a slide 70 is movably mounted on the standard 401 with one end positioned to engage the cam 306 and provided with a pin 10 70^a engaging in a slot in an end of a bell crank lever 71. The bell crank lever 71 is pivotally mounted, as at 71^a, on a bracket 72 carried by the standard 401. The opposite end of the lever 71 has an opening through which is inserted an end 15 of a wire or rod 73, the opposite end of which is pivotally connected to an end of a lever 74. Collars 41 fixed on the rod 73 insure movement of the lever 74 with the rod 73.

The lever 74 is pivotally mounted on the 20 bracket 21 above the lever 26 and the other end of the lever 74 extends beneath an end of a lever 75 which is pivotally mounted on the pin 29 carried by the supporting rod 30. Adjacent its other end the lever 75 is recessed as at 75^a and 25 at its end is provided with a cam engaging surface 75^b positioned to be engaged by a cam 76 mounted on a lever 77 which is pivotally supported on the pin 36. At its outer end the lever 77 is provided with an arm 78 which carries a 30 roller 79 positioned to engage the cam 40 in advance of the roller 36^a and held in engagement with cam 40 by a spring 80 attached to the end of the lever 77 and to a convenient point on the machine frame. The arrangement of the levers and cams is such that when the roller 79 is at the portion of the cam 40 of least radius, as in Fig. 1, the cam 76 is in the recess 75^a of the lever 75 permitting the lever to fall and the slide 70 to be moved forward by the spring 81 to shift the 40 cam 306 and the sinkers s to their advanced positions, and when the roller 79 is on portions of the cam 40 of greater radius the cam 76 is moved beneath the cam portion 75^b of the lever 75, the lever 75 is raised and the slide 70 is held retracted against the action of the spring 81, the cam 306 being moved outwardly by the action of the sinkers and the sinkers being guided by the fixed cam 307.

The rollers 79 and 36^a are positioned so as to 50 time the operations of the yarn finger F¹ for the reinforcing yarn and the operating cam 306 for the sinkers, the sinkers being operated to lengthen the loops drawn by the needles taking the reinforcing yarn and as the cam 40 is rotated synchronously with the needle cylinder the yarn finger F¹ and the cam 306 are operated during each revolution of the needle cylinder. To prevent operation of the sinkers by the cam 306 when the reinforcing yarn is not being fed to the needles there is provided a push rod 462 operated by cams on the main pattern drum 120 and provided with a lug 462^a which engages beneath the lever 74 when the push rod 462 is raised by the cams, as cams 121 and 123 on the 60 main pattern drum 120, and holds the slide 70 retracted when the yarn finger F¹ is held inoperative by corresponding cams of the main pattern drum and the push rod 460.

Both levers 28 and 75 are carried on the pin 29 70 mounted in the supporting rod 30 and are shifted bodily as the rod 30 is shifted by the operation of the ratchet 48 and cam 46. Shifting the levers 28 and 75 changes the relations of the recesses in these levers and the cam surfaces at their 75

ends with respect to the cams on the levers 34 and 77, respectively, and changes the period during which the cams 32 and 76 move in the recesses in the levers, thus changing the extent of 5 the portion of a revolution of the needle cylinder during which the reinforcing yarn is fed to the needles and the sinkers are held in the advanced position.

In the knitting of a stocking, which in the machine shown is knit beginning at the top, the push rod 460 is held in raised position by a cam 121 on the main pattern drum 120 and holds the reinforcing yarn finger F¹ out of action during the knitting of the stocking top and leg. During this 10 time the push rod 462 is also held in raised position by a cam 121 and the slide 70 is held retracted by the engagement of the lug 462^a on the push rod 462 with the lever 74, and the sinkers s are not advanced to their inner positions. During the 15 knitting of the top and leg the pawl 50 rides on the cam 48^a on the ratchet 48 and the ratchet 48 and cam 46 remain in position for starting the reinforcing of the high splice with the pin 30^b on the surface 46^c of the cam 46. Operation 20 of the main pattern drum 120 rotates the gear 56 and advances the pin 59 thereon towards the abutment 60 on the ratchet 48. At the beginning 25 of the high splice a racking movement of the main pattern drum shifts the cams 121 from beneath the push rods 460 and 462. Lowering the 30 push rod 460 lowers the reinforcing yarn finger F¹ to present the reinforcing yarn to the needles and positions the thrust rod 460 to be operated by the lever 26 from the cam 40 by means of the lever 35 28. Lowering the thrust rod 462 removes the spring 81 to lower the rod 73 and operate the slide 70 to shift the sinker operating cam 306 to a position for advancing the sinkers. Lowering the 40 lever 74 places this lever in position to be operated from the cam 40 by the lever 75. The yarn finger F¹ and sinker operating cam 306 are, accordingly, placed in operative position by the cam 40 for a portion of each revolution of the needle cylinder.

Knitting of the reinforced portion or high splice 45 continues with the pin 30^b resting on the cam surface 46^a of the cam 46 and causing the reinforced portion to be of uniform width until a further racking movement of the main pattern drum 120 brings the pin 59 on gear 56 into engagement with the abutment 60 on ratchet 48 and shifts ratchet 48 to move cam surface 48^a past the pawl 50 so that pawl 50 operates the ratchet 48 and cam 46 with a step by step motion. The portion 50 46^a of the surface of the cam 46 is moved from beneath the pin 30^b by the operation of the ratchet 48 by the pin 59 and upon movement of the surface 46^a from the pin 30^b the pin engages surfaces of different radii causing the rod 30 to shift, carrying with it the levers 28 and 75 and changing the relation of these levers to the levers 34 and 77 to produce a step by step increase in the portion of each revolution of the needle cylinder during which the yarn finger F¹ and the sinker operating cam 306 are held in their operative 55 positions and a gradual widening of the reinforced portion or high splice. The operation of the ratchet 48 and cam 46 by the pawl 50 gradually advances the abutment 60 on ratchet 48 away from the pin 59 on gear 56 and brings the pin 30^b in rod 30 onto the cam surface 46^b and the ratchet 48 to a position where the pawl 50 rides on the cam surface 48^b. Several courses are knit with reinforced portions of uniform width 60 while the pin 30^b is on the surface 46^b and the

main pattern drum 120 is then racked for the knitting of the heel bringing cams 123 on the drum 120 beneath the push rods 460 and 462 and raising the yarn finger F¹ to withdraw the reinforcing yarn from the needles and through the abutment 60 65 462^a on push rod 462 operating the lever 74 and the rod 73 to retract the slide 70 from the sinker operating cam 306. As the pawl 50 rides on the cam surface 48^b the ratchet 48 and cam 46 remain stationary throughout the knitting of the heel. 10

The rack of the main pattern drum 120 for the knitting of the heel advances the pin 59 on gear 56 towards the abutment 60 on ratchet 48 and upon the main pattern drum being racked at the finish of the knitting of the heel the pin 59 engages 15 the abutment 60 and shifts the ratchet 48 to move the cam surface 48^b from beneath the pawl 50 and permits the pawl 50 to again operate the ratchet 48 and cam 46. This rack of the main pattern drum 120 shifts the cams 123 from beneath the push rods 460 and 462 and returns the reinforcing yarn finger F and the sinker operating cam 306 to the control of cam 40 and the reinforcing yarn is fed to the needles for the reinforcing of the sole portion, the loops being 20 lengthened at the needles taking the reinforcing yarn by the operation of the sinkers by the cam 306. The pin 30^b rides on the cam surface 46^b during the knitting of several courses so that a reinforced portion of uniform width is knit and 25 the pin 30^b then passes to cam surfaces of different radii causing a shifting of the rod 30 and levers 28 and 75 with respect to the levers 34 and 77 and a step by step narrowing of the reinforced portion of the sole takes place until the pin 30^b 30 passes onto the surface 46^c of the cam 46. As the pin 30^b passes onto the surface 46^c the pawl 50 rides on the cam surface 48^c, stopping the rotation of the ratchet 48 and cam 46. As the pin 30^b passes onto the surface 46^c the pin 62 on the 35 ratchet 48 passes over the dog 64 and permits the dog 64 to rise in back in position to engage the pin 62. The knitting of the sole continues with the pin 30^b engaging the cam surface 46^c and causing a reinforced portion of uniform width 40 to be knit and the sinker operating cam 306 to operate the same sinkers during the knitting of each course thereof until a movement of the main pattern drum 120 causes a cam (not shown) on the drum 120 to operate lever 66 to engage the 45 pin 62 and shift the cam surface 48^c past the pawl 50 permitting the pawl 50 to advance the ratchet 48 and cam 46 and shift the rod 30 and levers 28 and 75 to gradually widen the reinforced portion of the sole and to increase 50 the number of sinkers operated by the cam 306 accordingly. The widening of the reinforced portion of the sole continues until a movement of the main drum for the knitting of the toe places the cams 121 beneath the push rods 460 and 462 to 55 raise the reinforcing yarn finger F¹ to withdraw the reinforcing yarn from the needles and, by means of abutment 462^a and lever 74, to raise the rod 73 and hold the slide 70 from the sinker operating cam 306. The rotation of the ratchet 48 60 and cam 46 by the pawl 50 continues during the knitting of the toe until the pawl 50 rides on the cam surface 48^a and stops further movement of the ratchet 48 and cam 46 with the ratchet and cam in position for beginning of the knitting of 65 the high splice of the next stocking.

While the use of a single reinforcing yarn has been shown and described it is to be understood that different reinforcing yarns may be used in the high splice and sole, the yarns being fed from 70 75

yarn fingers controlled as described and the sinker operating means being rendered operative each time a reinforcing yarn is presented to the needles and controlled with the reinforcing yarn finger to lengthen the loops drawn by needles taking the reinforcing yarn.

What is claimed is:

1. In a circular knitting machine having means for knitting fabric of a main or body yarn, means for feeding reinforcing yarn to the needles during the knitting of a plurality of courses of the fabric, means operating said feeding means, means controlling said operating means to vary step by step the number of needles taking the reinforcing yarn in the knitting of a course, sinkers over which the loops are drawn by the needles, said sinkers having positions for causing the needles to draw loops of different lengths, means operating sinkers to cause the longer loops to be drawn by the needles taking the reinforcing yarn, said sinker operating means operating independently of said yarn feed operating means and means for adjusting said sinker operating means in accordance with changes in the number of needles taking the reinforcing yarn.

2. In a circular knitting machine having means for knitting fabric of a main or body yarn, means for feeding a reinforcing yarn, means operating said feeding means to feed the reinforcing yarn to the needles during the knitting of a plurality of courses of the fabric, sinkers over which the loops are drawn by the needles, said sinkers having positions for causing the needles to draw loops of different lengths, means operating sinkers to cause the longer loops to be drawn by the needles taking the reinforcing yarn, said sinker operating means operating independently of said yarn feed operating means, means for adjusting each of said operating means to vary the number of needles taking the reinforcing yarn and the number of sinkers causing the longer loops to be drawn in the knitting of a course and means for simultaneously operating said adjusting means step by step.

3. In a circular knitting machine having means for knitting fabric of a main or body yarn, means for feeding a reinforcing yarn, sinkers over which the loops are drawn by the needles, said sinkers having positions causing the needles to draw loops of different lengths, means operating said feeding means to feed reinforcing yarn to the needles during the knitting of a plurality of courses of the fabric, means operating said sinkers to cause the longer loops to be drawn by the needles taking the reinforcing yarn, each of said operating means comprising cooperating cam surfaces, and means for relatively shifting said cooperating cam surfaces of both operating means to vary step by step the number of needles taking the reinforcing yarn and the number of sinkers causing the longer loops to be drawn in the knitting of a course.

4. In a circular knitting machine having means for knitting fabric of a main or body yarn, means for feeding a reinforcing yarn, sinkers over which the loops are drawn by the needles, said sinkers having positions causing the needles to draw loops of different lengths, means operating said feeding means to feed reinforcing yarn to the needles during the knitting of a plurality of courses of the fabric, means operating said sinkers to cause the longer loops to be drawn by the needles taking the reinforcing yarn, each of said operating means comprising cooperating cam surfaces, a cam for relatively shifting said

cooperating cam surfaces of both operating means to vary the number of needles taking the reinforcing yarn and the number of sinkers causing the longer loops to be drawn in the knitting of a course, and means for operating said cam step by step.

5. In a circular knitting machine, yarn fingers for feeding main and reinforcing yarns to the needles, means operating said reinforcing yarn finger to feed yarn to needles in each of a plurality of courses, means for adjusting said operating means to position said yarn finger to feed reinforcing yarn to different numbers of needles in different courses, sinkers over which loops are drawn by the needles, said sinkers being operable to positions for the drawing of loops of different lengths by said needles, means for operating sinkers to their position for the drawing of loops of the greater length by the needles taking the reinforcing yarn comprising a cam for engaging the sinkers, a lever for operating said cam, a link connected to said lever, a second lever connected to said link, means for operating said second lever, and means for adjusting the operation of said sinker operating means to vary the number of sinkers causing needles to draw the longer loops in accordance with variations in the number of needles taking the reinforcing yarn.

6. In a circular knitting machine, yarn fingers for feeding main and reinforcing yarns to the needles, means for operating said reinforcing yarn finger to feed yarn to needles in each of a plurality of courses, means for adjusting said operating means to vary step by step the number of needles taking said reinforcing yarn in different courses, sinkers over which loops are drawn by the needles, said sinkers being operable to positions for the drawing of loops of different lengths by said needles, means for operating sinkers to their position for the drawing of loops of the greater length by the needles taking the reinforcing yarn comprising a cam for engaging the sinkers, a lever for operating said cam, a link connected to said lever, a second lever connected to said link, means for operating said second lever, and means for adjusting the operation of said sinker operating means to vary the number of sinkers causing needles draw the longer loops in accordance with variations in the number of needles taking the reinforcing yarn.

7. In a circular knitting machine, yarn fingers for feeding main and reinforcing yarns to the needles, means for operating said reinforcing yarn finger to feed yarn to needles in each of a plurality of courses, adjusting means for said operating means comprising a cam and means for operating said cam to vary step by step the number of needles taking said reinforcing yarn in different courses, sinkers over which loops are drawn by the needles, said sinkers being operable to positions for the drawing of loops of different lengths by said needles, means for operating sinkers to their position for the drawing of loops of the greater length by the needles taking the reinforcing yarn comprising a cam for engaging the sinkers, a lever for operating said cam, a link connected to said lever, a second lever connected to said link, means for operating said second lever, and means for adjusting the operation of said sinker operating means to vary the number of sinkers causing needles to draw the longer loops in accordance with variations in the number of needles taking the reinforcing yarn.

8. In a circular knitting machine, yarn fingers for feeding main and reinforcing yarns to the

- needles, operating means for positioning said reinforcing yarn finger to feed yarn to needles in each of a plurality of courses, adjusting means for said operating means comprising cooperating 5 cam surfaces and means for relatively shifting said cam surfaces to vary step by step the number of needles taking the reinforcing yarn in different courses, sinkers over which loops are drawn by the needles, said sinkers being operable 10 to positions for the drawing of loops of different lengths by said needles, means for operating sinkers to their position for the drawing of loops of the greater length by the needles taking the reinforcing yarn comprising a cam for engaging the sinkers, a lever for operating said cam, a link connected to said lever, a second lever connected to said link, means for operating said second lever, and means for adjusting the operation of said sinker operating means to vary 15 the number of sinkers causing needles to draw the longer loops in accordance with variations in the number of needles taking the reinforcing yarn.
- 15 9. In a circular knitting machine, yarn fingers for feeding main and reinforcing yarns to the needles, operating means for positioning said reinforcing yarn finger to feed yarn to needles in each of a plurality of courses, adjusting means for said operating means comprising cooperating cam surfaces and a cam for relatively shifting 20 said cooperating cam surfaces to vary step by step the number of needles taking the reinforcing yarn in different courses, sinkers over which loops are drawn by the needles, said sinkers being 25 operable to positions for the drawing of loops of different lengths by said needles, means for operating sinkers to their position for the drawing of loops of the greater length by the needles taking the reinforcing yarn comprising a cam for engaging the sinkers, a lever for operating said cam, a link connected to said lever, a second lever connected to said link means for operating said second lever, and means for adjusting the operation of said sinker operating means to vary 10 the number of sinkers causing needles to draw the longer loops in accordance with variations in the number of needles taking the reinforcing yarn.
- 20 10. In a circular knitting machine having 15 means for knitting fabric of a main or body yarn, means for feeding reinforcing yarn to the needles during the knitting of a plurality of courses of the fabric, means, including a push rod, for operating said feeding means, means 20 controlling said operating means to vary step by step the number of needles taking the reinforcing yarn in the knitting of a course, sinkers over which the loops are drawn by the needles, said sinkers having positions for causing the needles 25 to draw loops of different lengths, means, including a push rod, for operating sinkers to cause the longer loops to be drawn by the needles taking the reinforcing yarn and means for adjusting said sinker operating means in accordance with changes in the number of needles taking the reinforcing yarn.
- 25 30 EDWARD PELOQUIN.
